UNITED STATES PATENT OFFICE

2,259,368

SELF-CONTAINED RAIL BOND STUD
TERMINAL

Harold H. Febrey, South Orange, N. J., assignor to
The American Steel and Wire Company of New
Jersey, a corporation of New Jersey

Application April 17, 1941, Serial No. 389,051

2 Claims. (Cl. 287—20.3)

This invention relates to rail bond stud terminals of the type adapted for installation by way of bottomed rail holes or recesses, and is particularly concerned with signal bond stud terminals of the type installed in bottomed holes or recesses formed in the sides of the rail heads.

A specific example of a signal bond having terminals embodying the principles of the present invention is illustrated by the accompanying drawing showing the bond with the terminals in the rail holes in longitudinal section, the left-hand terminal being shown prior to its being fixed in position and the right-hand terminal being shown after being fixed.

More specifically, in this drawing the terminal is shown as having a head 1 and a stud 2 with a hole opening from the side of the head opposite the stud and extending through the head and into the stud, the hole terminating inside the stud and the portion 3 of the hole within the stud 2 having a smaller diameter than a portion 4 of the hole within the head including the opening to the hole. A malleable metal insert 5 is positioned in the portion 3 of the hole with an end extending toward the portion 4 and terminating short of the junction 6 between the portions 3 and 4. This junction is slightly above the junction between the terminal stud and head. A tool is retained in the hole with an end 7 exposed beyond the side of the head 1 opposite the stud 2, this tool having a portion 8 fitting the hole portion 4 and an end portion 9 fitting the hole portion 3.

All the portions of the hole and of the tool are cylindrical and the tool is press-fitted into the hole so that the terminal is self-contained. Hammer blows on the exposed end 7 drive the tool down into the hole so that its end 9, which contacts the insert 5, applies compressive force to the insert 5 so as to effect expansion of the stud 2. As previously mentioned, the left-hand terminal in the drawing shows the terminal before its stud has been expanded while the right-hand terminal is shown as it appears after its stud has been expanded.

One advantage of the new terminal is that it

permits the stud 2 to have a sufficiently thick wall to permit removal of the terminal without fear of stud breakage, while at the same time providing an expanding pin or tool that has a force receiving end that is sufficiently large in diameter to insure it against being broken when struck by a hammer. It will be noted that the expansive force is confined entirely to the stud. In addition to these advantages, the new terminal 10 has the great advantage that the tool it carries is provided with double guiding bearings for positively preventing tilting of the tool by a carelessly struck hammer blow, this being important since such tilting would jam the tool in the terminal hole and prevent proper use of the terminal.

I claim:

1. A rail bond terminal having a head and a stud with a hole opening from the side of the head opposite the stud and extending through the head and into the stud, the hole terminating inside the stud and the portion of the hole within the stud having a smaller diameter than a portion of the hole within the head including the opening to the hole, a malleable insert positioned in the first named portion of the hole with an end extending toward the second named portion and terminating short of the junction between the two named portions, and a tool retained in the hole with an end exposed beyond said side of the head and having a portion fitting the second named hole portion and an end portion bearing on the insert and fitting the first named hole portion.
2. A rail bond terminal having a head and stud with a hole formed through said head and into said stud, said hole having a relatively larger diameter within said head and a relatively smaller diameter within said stud containing an insert, and a tool carried by said terminal with a portion fitting said large diameter portion of said hole and another portion fitting said small diameter portion of said hole, whereby said tool is provided with a double bearing to prevent its canting when put to use to expand said insert.

HAROLD H. FEBREY.
